PUMP

Ralph K. Londa, Detroit, Mich., assignor to Holley Carburetor Company, Warren, Mich., a corporation of Michigan

Filed July 1, 1964, Ser. No. 379,618
8 Claims. (Cl. 103—38)

This invention relates generally to pumps, and more particularly to a positive displacement, constant pressure, variable stroke, eccentric drive pump.

In the prior art constant pressure, variable stroke, eccentric driven pumps, when the eccentric engages an abutment member of the partially de-stroked pump assembly, an extremely high acceleration of fuel results so as to cause excessive pressure pulses. These excessive pressure pulses are detrimental to the operation of systems in which the pump is employed. Additionally the engagement of the eccentric with the partially de-stroked pump assembly requires considerable force because the eccentric must move not only the abutment member assembly but also the bulk of fluid being pumped and; as a result, prior art pump assemblies of this construction have been subject to failure after a relatively short life.

Accordingly, a general object of the invention is to provide an improved constant pressure, variable stroke, eccentric drive pump which is smoother in operation and less subject to failure.

A more specific object of the invention is to provide such a pump wherein the eccentric contacts the abutment member so as to move it in a de-stroking (suction) direction, rather than in the pumping direction; thus, the eccentric does not move the bulk of fluid being pumped, the latter function being handled by a spring drive system.

A further object of the invention is to provide such a pump wherein an additional shock absorbing and pressure pulse reducing feature may be incorporated, if desired.

Other objects and advantages of the invention will become apparent when reference is made to the following specification and the accompanying drawings wherein:

FIGURE 1 is a cross-sectional view of a pump embodying the invention.

FIGURE 2 is a view taken along the plane of line 2—2 of FIGURE 1, and looking in the direction of the arrows.

FIGURE 3 is a fragmentary cross-sectional view taken along the plane of line 3—3 of FIGURE 2 and looking in the direction of the arrows.

FIGURE 4 is a view taken along the plane of line 4—4 of FIGURE 3, and looking in the direction of the arrows. It will be noted that FIGURES 2 and 4 are unorthodox in that they are taken as if FIGURES 1 and 3, respectively, were side elevational views.

FIGURE 5 is an enlarged cross-sectional view of a modification of the invention.

FIGURE 6 is a fragmentary portion of FIGURE 5, to illustrate a modification thereof.

Before discussing the drawings in detail, it should be understood that the various chambers of the pump shown are of a cylindrical construction. That is, the cross-sectional views shown by FIGURES 1 and 5 are adequate for a complete disclosure because they are taken on a symmetrical plane.

Referring now to the drawings in greater detail, FIGURE 1 illustrates a pump assembly 10 which includes a multiple piece, substantially cylindrical housing 12, fastened together as by screws 13 and containing an eccentric 14. The eccentric 14 is fixedly secured to a rotatable shaft 16, as by means of a key 18 confined in grooves formed in the outer surface of the shaft and the inner surface of the eccentric. The shaft 16 may rotate within bearings 19 secured in the housing 12. The housing 12

2

further includes a plurality of chambers 20, 22, 24 and 26, which are hereinafter referred to as the central chamber, the accumulator chamber, the pumping chamber and the discharge chamber, respectively.

5 Pressure responsive devices, such as diaphragms 28 and 30, form movable walls between the central chamber 20 and the accumulator chamber 22 and between the central chamber 20 and the pumping chamber 24, respectively. The diaphragm 28 may comprise a continuous circular piece of suitable material having washers 32 and 34 adjacent the opposite sides thereof, whereas the diaphragm 30 includes a central opening 36.

A piston assembly 37 is affixed to the diaphragm 30 in the central chamber 20. The assembly 37, better seen in FIGURES 2, 3 and 4, includes a hollow member 38 which straddles the end faces of the eccentric 14 and has a pair of elongated openings 40 formed through the opposing sides thereof for passage of the shaft 16, as well as a second pair of elongated openings 41 formed perpendicular thereto. One end of the hollow member 38 includes a flange 42 which is fixedly secured to the diaphragm 30 and to a diaphragm center cover 44 by means of rivets 46. The diaphragm cover 44 includes a central opening 48 and a plurality of radial openings 50. The flanged end 42 of the member 38 is counterbored to receive a check valve 52 which is urged against the counterbored seat 54 by a spring 56 located between the check valve 52 and the diaphragm cover 44. A plurality of additional openings 57 may be formed through the wall 30 of the member 38 intermediate the openings 41 and the flange 42 for free passage of fluid therethrough. A hardened striker plate 58 may be pressed into the hollow member 38 against its solid end 59.

Referring again to FIGURE 1, the pumping chamber 24 and the discharge chamber 26 are separated by a fixed wall 60 having an opening 61 formed therethrough. A second check valve is urged against the opening 61 by a spring 64 mounted in the discharge chamber 24.

A larger spring 66 mounted between the flange 42 of the hollow member 38 and a fixed spring retainer 68 in the central chamber 20 urges the diaphragm 30 and the assembly 37 to the right in FIGURE 1, thereby decreasing the volume of the pumping chamber 24 for a purpose to be described later. A still larger drive spring 70 is also mounted in the central chamber 20 between the cup-shaped washer 34 and a flanged seat member 72 abutting against the solid end 59 of the hollow member 38. A plurality of ports 76 are formed through the flanged member 72 to allow free passage of fluid therethrough. Movement of the washer 34 to the right is limited by a mechanical stop comprising an annular abutment 78 formed in the central chamber 20.

An inlet 80 to the central chamber 20 may be formed in a wall of the housing 12, and an outlet 82 from the discharge chamber 26 is formed in the end wall of the housing. A conduit, represented schematically by the line 84, communicates between the outlet 80 and the accumulator chamber 22. Another conduit 86 may branch off the conduit 84 at any convenient point for supplying pumped fluid, such as fuel, to any suitable device (not shown) requiring the same.

Operation

65 Fuel or other fluid to be pumped enters the central chamber 20 via the inlet 80 from any suitable source (not shown). As the eccentric 14 is rotated by the shaft 16 through one complete cycle, the high side of the eccentric 14 will alternately abut against and then leave contact with the striker plate 58 of the piston assembly 37. While the high side of the eccentric 14 is in contact with the striker plate 58, the flanged member 72 will be moved to the left in FIGURE 1 against the force of

the spring 70, thereby also moving the diaphragm 28 to the left.

Since this is the suction stroke, the volume of the pumping chamber 24 will be increased, causing the check valve 52 to leave its seat 54 against the force of the spring 56 and permitting fuel to flow from the central chamber 20 into the pumping chamber 24. During this suction stroke, the discharge check valve 62 will be held against its seat by the combined forces of the spring 64 and the pressure of the fluid in and downstream of the discharge chamber 26. The pressure in the discharge chamber 26 is maintained by virtue of the large spring 70 in the central chamber 20 having urged the diaphragm 28 to the left, as just described. This leftward movement of the diaphragm 28 not only maintains the pressure within the discharge and accumulator chambers 26 and 22, respectively, but it also serves to supply the required flow through the conduits 84 and 86 to the equipment supplied by the pump.

Once the high side of the eccentric 14 leaves contact with the striker plate 58, the springs 66 and 70 will begin to move the piston assembly 37, and the diaphragm 30, to the right in FIGURE 1 on its pumping stroke. The spring 66 is required in this particular embodiment because the areas of the diaphragms 28 and 30 are substantially equal so as to be subjected to substantially equal forces. Obviously, if the diaphragm 30 were smaller in area than the diaphragm 28, the spring 66 would not be required since the spring 70 would, on its own, move the piston assembly 37 to the right against the lesser force adjacent the smaller diaphragm. In either event, the movement to the right will force the check valve 52 closed and the discharge check valve 62 open, against the force of the relatively small spring 64, and discharge fluid out of the pumping chamber 24, into the discharge chamber 26 and through the outlet 82 and thence through the conduit 84 to the supply conduit 86, as well as to the accumulator chamber 22, thereby recharging the accumulator diaphragm 28 until the washer 34 contacts the abutment 78.

FIGURE 5 modification

In the FIGURE 5 embodiment, all elements which are similar to corresponding elements in FIGURE 1 bear the same reference numerals. The principal difference between FIGURES 5 and 1 is that the diaphragm 30 and piston assembly 37 of FIGURE 1 have been replaced by a piston assembly 92 that eliminates the need for a diaphragm similar to the diaphragm 30 of FIGURE 1.

The piston assembly 92 includes an outer cylindrical member 94 having opposing openings 96 formed therein for passage of the shaft 16. A pair of plates 98 and 100 are fixedly secured to the right end of the cylindrical member 94, as by screws 102, and are slidably fitted within the walls of the central chamber 20. The plate 100 is undercut to receive a seal 104 which prevents leakage between the central chamber 20 and the pumping chamber 24.

The left end of the piston assembly 92 includes a member 106 which is similar in function to the striker plate 58 of FIGURE 1; however, member 106 includes a pocket 108 suitable for receiving an extension 110 formed on a rocker arm 112. The rocker arm 112 is secured to a bushing 114, as by screws 116, the latter assembly being fitted around the usual eccentric 14. A resilient disk 118 may be fitted between the member 106 and the end 120 of the cylindrical member 94 in order to help absorb any shock resulting from the high side of the eccentric 14 causing the extension 110 to impact the bottom of the pocket 108.

It is obvious that the FIGURE 5 modification operates in the same general manner as the FIGURE 1 embodiment; thus, a discussion of the operation need not be repeated. It should be noted, however, that the FIGURE 5 embodiment does not include a spring 66, as illustrated in FIGURE 1, since the pumping area of the plate 100

of the piston assembly 92 is considerably smaller than the area of the accumulator diaphragm 28. Hence, as previously explained, the spring 70 will move the piston assembly 92 to the right in FIGURE 5 during the pumping stroke, supplying output flow and recharging the accumulator.

FIGURE 6 modification

A shock absorbing system 122 may be substituted for the resilient disk 118 arrangement illustrated in FIGURE 5. As illustrated in FIGURE 6, a resilient member 124 is confined between and securely fastened at its inner and outer surfaces to members 126 and 128 which are equivalent to the members 106 and 120 of FIGURE 5.

It should be apparent that, as the extension 110 is moved to the left into contact with the bottom of the pocket 130 formed in the member 126 by the eccentric 14, the member 126 will make its initial leftward movement before the member 128 is caused to move, due to the "give" in the intermediate resilient ring 124. Thus, the instantaneous inertia forces on the various pump assembly components are lower, tending to prolong the life thereof; also, the instantaneous pressure increase on the diaphragm 28 is likewise lower, tending to reduce pressure pulses through the conduits 84 and 86 to the equipment supplied by the pump. If desired, the FIGURE 6 arrangement could be incorporated in the FIGURE 1 structure merely by reworking the end 59 and striker plate 58 thereof.

Summary

It should be readily apparent that, as compared to prior art eccentric driven pumps, the invention presents a novel dual approach in increased pump life and decreased pressure surges or pulses downstream of the pump. In other words, the use of the eccentric to actuate the suction stroke and a spring to actuate the pumping stroke will produce such advantages. These advantages may be made even more pronounced by the addition of the resilient means described in connection with FIGURE 6.

While a preferred embodiment and two modifications have been shown and described for purposes of illustration, other modifications may be possible within the scope of the following claims:

- What I claim as my invention is:
45. 1. A pump assembly, comprising a chamber including a shaft having an eccentric formed thereon, an inlet and an outlet, a pump element at times being moved by said eccentric away from said outlet; an accumulator chamber; a passageway communicating between said accumulator chamber and said outlet; a pressure responsive device forming a movable wall between said first mentioned chamber and said accumulator chamber; and a spring mounted between said pressure responsive device and said pump element for urging said pump element toward said outlet when said pump element is not being moved by said eccentric.
  50. 2. A pump assembly, comprising a chamber including a shaft having an eccentric formed thereon, an inlet and an outlet, a pump element at times being moved by said eccentric away from said outlet; an accumulator chamber; a passageway communicating between said accumulator chamber and said outlet; a pressure responsive device forming a movable wall between said first mentioned chamber and said accumulator chamber; and a spring mounted between said pressure responsive device and said pump element urging said pump element toward said outlet when said pump element is not being moved by said eccentric and for simultaneously urging said pressure responsive device away from said outlet so as to maintain the pressure and flow downstream of said outlet.
  55. 3. The device is described in claim 2, wherein said pump element is a diaphragm assembly.
  60. 4. The device as described in claim 2, wherein said pump element is a piston assembly.

5. A pump assembly comprising a housing having first, second, third and fourth chambers formed therein, a shaft rotatably mounted through said first chamber, an eccentric fixedly mounted on said shaft within said first chamber, a first pressure responsive device forming a movable wall between said first and second chambers, a second pressure responsive device forming a movable wall between said first and third chambers, a first spring-biased check valve between said third and fourth chambers, a second spring-biased check valve in said second pressure responsive device, a pump element slidably mounted in said first chamber and fixedly secured to said second pressure responsive device, and a spring mounted between said pump element and said first pressure responsive device, said pump element at times being moved by said eccentric toward said first pressure responsive device against the force of said spring.

6. The device as described in claim 5, wherein said first and second pressure responsive devices are diaphragm assemblies.

7. The device as described in claim 5, wherein said first pressure responsive device is a diaphragm assembly and said second pressure responsive device is a piston assembly.

8. A pump assembly, comprising a housing having first, second, third and fourth chambers formed therein;

a shaft rotatably mounted through said first housing; an eccentric fixedly mounted on said shaft within said first chamber; a first pressure responsive device forming a movable wall between said first and second chambers; a second pressure responsive device forming a movable wall between said first and third chambers; a first spring-biased check valve between said third and fourth chambers; a second spring-biased check valve in said second pressure responsive device; a pump element slidably mounted in said first chamber and fixedly secured to said second pressure responsive device; a member in sliding contact with said eccentric; resilient means secured between said member and said pump element; and a spring mounted between said pump element and said first pressure responsive device; said member, said resilient means and said pump element at times being moved by said eccentric toward said first pressure responsive device against the force of said spring.
